UNITED STATES PATENT OFFICE.

WINTWORTH V. LANDER, OF NEWTON, MASSACHUSETTS.

CHLORINATING APPARATUS.

No. 841,329.

Specification of Letters Patent.

Patented Jan. 15, 1907.

Application filed April 27, 1906. Serial No. 313,923.

To all whom it may concern:

Be it known that I, WINTWORTH V. LANDER, a citizen of the United States, and a resident of Newton, in the county of Middlesex and State of Massachusetts, have invented new and useful Improvements in Chlorination Apparatus, of which the following is a specification.

My invention relates to apparatus for the chlorination of ores; and it consists in sundry improvements in such apparatus by which I obtain increased efficiency and saving in materials, labor, and power.

My apparatus is suited to and in most cases involves the performance of an improved process of ore chlorination, which for the sake of illustration will be described hereinbelow. This process forms the subject-matter of an application for Letters Patent of the United States, Serial No. 313,922, filed by me concurrently herewith and is expressly reserved for claim therein.

In the drawing hereto annexed my improved apparatus is illustrated in longitudinal section.

In the drawing, A represents a head-chamber into which comminuted ore is delivered, as from a superposed hopper II. The bottom of this head-chamber terminates in a lip 30 or dry weir at A', over which the ore is delivered in a cascade upon the riffle presently to be described. The ore-feed may be secured in a number of different ways. The mode which I prefer is, as illustrated, to provide a feed-screw G, projecting into the head-chamber A and driven by some suitable appliance, as the pulley G' on the outside. This head-chamber together with the hopper above it are proportioned with relation 35 to the character and degree of comminution of the mass of ore-carrying earth or rock to be treated, so that so long as the supply is maintained in the hopper II the head-chamber A will be completely full from base to 40 top, and it will thus be difficult, if not impossible, for any gases within the apparatus to escape by backing up through the head-chamber and hopper. Below the delivery end of the head-chamber A, I arrange a 45 water-intake chamber F², which receives water through the pipe F, preferably through a strainer-plate F', which will serve to distribute the stream and prevent undue disturbances or gushes of liquid from the pipe F. To the delivery ends of the head-cham-

ber A and water-intake F², I secure the upper section B of the sectional riffle-pipe, making a gas-tight joint. The sections B of the riffle-pipes are composed, preferably, of glazed tile or other refractory earthenware which will 60 effectually resist the attacks of chlorin, and, moreover, I prefer to employ pipe-sections B which are square in cross-section. Each of the sections B is joined and hermetically sealed to its neighbor, as by the flanges B', 65 and in the tops of each of these sections B are provided tightly-covered hand-holes, as at B². When the sections B are assembled, they form an inclined pipe, the angle of inclination being about one foot in ten. Each 70 pipe-section B is provided with a riffle-plate C, which, like the pipe, should be constructed of refractory material, as glazed tile, and sealed, as by burning and glazing, to the interior of the pipe-section itself. The riffles 75 when the apparatus is in position are set at a slight angle to the axis of the pipe, so that each riffle is nearly horizontal, just enough inclination being given to it to offset the friction between a stream of liquid running over 80 the plate and the plate itself, so that the stream may be as nearly as possible of uniform depth. Each riffle-plate C is provided with transverse corrugations or ridges, as E, 85 and projects a slight distance beyond the end of the pipe-section, as at D. A riffle-pipe of this character extending for about fifty feet will probably be sufficient for all practical purposes, although I consider it desirable to extend this pipe considerably farther and to 90 make it in some instances at least two hundred feet in length. The length of the pipe will be determined for each case according to the nature of the ore and the concentration of chlorinated water. Each section B need 95 not be longer than eighteen inches, so that there will be in the pipe when assembled a large number of riffle-sections, each overhanging the next, as at the points marked D in the drawing.

The lower or delivery section of the riffle-pipe delivers into the receiving-tank K. Means should be provided whereby the receiving-tank K shall be gas-tight with the riffle-pipe, and for this purpose I have indicated the construction of the hood K', which slips over the delivery end of the riffle-pipe and may be sealed thereto, as by a rubber gasket or packing-ring. The tank K should, moreover, be removable or capable of discon-

nection from the riffle-pipe B, and for this purpose I have indicated the arrangement shown in the drawing—namely, rails or runways L, upon which the tank K is mounted by means of small wheels or riffles K⁵. The runway L is also mounted on trucks, as at L', so that it may be removed with the tank transversely to the axis of the riffle-pipe itself. If the tanks used are too large for such manipulation, the connections may be by large rubber hose-pipe. In order to provide means to sample the liquor in the tank K, I show in the drawings a trough and sampling-elbow at K² and K³, covered by the cap K⁴, or instead of this the covered opening K⁵ may be used, through which a sampling-tube can be inserted to draw out liquid from the tank.

The operations of the apparatus and the conduct of my improved process are as follows: Simultaneously ore is sprinkled in a cascade from the dry weir A' upon the head riffle and chlorinated water is introduced upon the riffle through the pipe F. This water may have been chlorinated by a process of preliminary preparation, or clear—that is to say, unchlorinated—water may be brought through the pipe F and a stream of chlorin gas, as through the pipe M, mingled therewith just before it enters the ore-chlorinating apparatus. The ore and chlorinated water mingled at the head of the riffle-pipe will proceed as one stream, being agitated by the riffle-ridges E and still further agitated by falling in cascades from one riffle-plate to the other, as at the points marked D, until finally the solution falls from the delivery end of the lowest riffle-plate in the series into the tank K. If the chlorinated water entering the apparatus carries chlorin in sufficiently concentrated solution, an atmosphere of chlorin will be maintained thereby in the riffle-pipes. The presence and maintenance of this atmosphere is of value in the process, for the reason that as the chlorinated water becomes exhausted or depleted by its reaction upon the soluble portions of the ore it has an opportunity by being agitated in the presence of and falling in occasional cascades through this atmosphere of chlorin to become regenerated and reinforced during the continuance of the chlorination process itself so that the chlorinated water is to all practical intents and purposes just as vigorous at the lower end of the series of riffle-plates as it is at the head. This renders the chlorin action effective at all stages and promotes the solution of the smaller and smaller residues of soluble matter. The insoluble portions of the mass of metal containing earth or rock are detained by the riffle-plates and retarded and classified according to their size, specific gravity, &c. The grooves between the riffle-ridges gradually fill up with these insoluble concentrates, the filling proceeding gradually from the head of the riffle-pipe to-

ward its foot. When by means of samples taken from the tank the process is observed to have proceeded far enough, the flow of chlorinated water is cut off, and clear—that is to say, unchlorinated—water substituted, which flowing gently through the riffle and over the concentrates washes out any chlorin which may remain absorbed therein and likewise clears the riffle-pipe of its chlorin atmosphere. When this last cleaning operation is finished, the receiving-tank is removed from its connection with the riffle-pipes, which may in turn be connected by any suitable means to a wash-tank. The uppermost hand-hole B² is then opened and a vigorous stream of water (as by a hose) is turned into the riffle-pipe and the riffle washed out, the concentrates being sent down the pipe. By washing successively in this way through each of the hand-holes B² the concentrates are deposited in the wash-tank. The subsequent treatment of the chlorids in the receiving-tank and of the concentrates in the wash-tank will depend upon the requirements of each particular operator and need not differ from the processes now in vogue.

The above-described process has the advantage of being continuously and uniformly effective during the whole period between charging and discharging the apparatus. By connecting the receiving-tank with suitable chlorinating-towers or gas-tanks the residues of chlorin gas from the process may readily be saved to be used over again, so that by continuous operation in rotation by several such apparatus as above described an economical and effective cycle can be maintained. Moreover, all the discomfort and danger to workmen from the escape of chlorin-gas is eliminated by the confinement of the gas in a continuous closed system, which is not opened to the air until all chlorin gas has been washed out.

What I claim, and desire to secure by Letters Patent, is—

1. In an apparatus for treating ores, a riffle-pipe, riffles therein, a head-chamber, an ore-hopper communicating therewith, the head-chamber provided with an ore-delivering mouth communicating with the head of the riffle-pipe, a duct communicating with the head of the riffle-pipe, to deliver liquid to and upon the riffle, a receiving-tank into which the foot of the riffle-pipe delivers, said tank and pipe forming a gas-tight system, and said chamber adapted to be filled with ore and to be made gas-tight thereby.

2. In an apparatus for treating ores, a riffle-pipe composed of pipe-sections, a riffle in each section projecting therefrom at the foot thereof to overhang the head of the riffle of the next section, a head-chamber, an ore-hopper communicating therewith, the head-chamber provided with an ore-delivering mouth communicating with the head of the

riffle-pipe, a duct communicating with the head of the riffle-pipe, to deliver liquid to and upon the riffle, a receiving-tank into which the foot of the riffle-pipe delivers, said tank and pipe forming a gas-tight system, and said head-chamber adapted to be filled with ore and to be made gas-tight thereby.

3. In an apparatus for treating ores, a riffle-pipe, riffles therein, a head-chamber, an ore-hopper communicating therewith, the head-chamber provided with an ore-delivering mouth communicating with the head of the riffle-pipe, a duct communicating with the head of the riffle-pipe, to deliver liquid to and upon the riffle, a receiving-tank, a hood thereon fitting the foot of the riffle-pipe, said tank, pipe, and hood forming a gas-tight system, and said head-chamber adapted to be filled with ore and to be made gas-tight thereby.

4. In an apparatus for treating ores, a riffle-pipe, riffles therein, a head-chamber, an ore-hopper communicating therewith, the head-chamber provided with an ore-delivering mouth communicating with the head of the riffle-pipe, a duct communicating with the head of the riffle-pipe, to deliver liquid to and upon the riffle, a receiving-tank into which the foot of the riffle-pipe delivers, said tank, pipe and head-chamber closed to form a continuous gas-tight system.

5. In an apparatus for treating ores, a riffle-pipe composed of pipe-sections, a riffle in each section projecting therefrom at the foot thereof to overhang the head of the riffle of the next section, a head-chamber, an ore-hopper communicating therewith, the head-chamber provided with an ore-delivering mouth communicating with the head of the riffle-pipe, a duct communicating with the head of the riffle-pipe, to deliver liquid to and upon the riffle, a receiving-tank into which the foot of the riffle-pipe delivers, said tank, pipe-sections, and head-chamber closed to form a continuous gas-tight system.

6. In an apparatus for treating ores, a riffle-pipe composed of pipe-sections, a riffle in each section projecting therefrom at the foot thereof to overhang the head of the riffle of the next section, hand-holes and covers therefor in the pipe-sections, a head-chamber, an ore-hopper communicating therewith, the head-chamber provided with an ore-delivering mouth communicating with the head of the riffle-pipe, a duct communicating with the head of the riffle-pipe, to deliver liquid to and upon the riffle, a receiving-tank into which the foot of the riffle-pipe delivers, said tank and pipe forming a gas-tight system, and said head-chamber adapted to

be filled with ore and to be made gas-tight thereby.

7. In an apparatus for treating ores, a riffle-pipe, riffles therein, a head-chamber, an ore-hopper communicating therewith, the head-chamber provided with an ore-delivering mouth communicating with the head of the riffle-pipe, a duct communicating with the head of the riffle-pipe, to deliver liquid to and upon the riffle, a receiving-pipe into which the foot of the riffle-pipe delivers, said tank and pipe forming a gas-tight system, and said head-chamber adapted to be filled with ore and to be made gas-tight thereby, the tank movably mounted to be removed from the foot of the riffle-pipe.

8. In an apparatus for treating ores, a riffle-pipe, riffles therein, a head-chamber, an ore-hopper communicating therewith, the head-chamber provided with an ore-delivering mouth communicating with the head of the riffle-pipe, a duct communicating with the head of the riffle-pipe, to deliver liquid to and upon the riffle, a receiving-tank, a hood thereon fitting the foot of the riffle-pipe, said tank, pipe and hood forming a gas-tight system, and said head-chamber adapted to be filled with ore and to be made gas-tight thereby, the tank movably mounted to be removed with its hood from the foot of the riffle-pipe.

9. In an apparatus for treating ores, a riffle-pipe, riffles therein, a head-chamber, an ore-hopper communicating therewith, a dry weir projecting into the head of the riffle-pipe from the head-chamber, to deliver ore to the riffles, means to feed ore through the head-chamber, a duct communicating with the riffle-pipe below the dry weir to deliver liquid to the riffle, a receiving-tank into which the foot of the riffle-pipe delivers, said tank, pipe and head-chamber closed to form a continuous gas-tight system.

10. In an apparatus for treating ores, a riffle-pipe, riffles therein, a head-chamber, an ore-hopper communicating therewith, a dry weir projecting into the head of the riffle-pipe from the head-chamber, to deliver ore to the riffles, means to feed ore through the head-chamber, a duct communicating with the riffle-tank into which the foot of the riffle-pipe delivers, said tank and pipe forming a gas-tight system, and said chamber adapted to be filled with ore and made gas-tight thereby.

Signed by me at Boston, Suffolk county, Massachusetts, this 23d day of April, 1906.

WINTWORTH V. LANDER.
